MAIL BOX

Edward Popp, El Campo, Tex.

Application May 9, 1939, Serial No. 272,686

7 Claims. (Cl. 232—39)

This invention relates to a mail box, and it is primarily an object of the invention to provide a box supported for swinging movement so that said box in one of its positions serves to give notice that mail has been left by the postman. It is also an object of the invention to provide a box of this kind mounted for swinging movement, together with means for holding said box in one position and automatically moving the box to a second position after the holding means has been made effective.

The invention consists in the details of construction and in the combination and arrangement of the several parts of my improved mail box whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawing, wherein:

Figure 1 is a fragmentary view in side elevation of a mail box constructed in accordance with an embodiment of my invention;

Figure 2 is a view in front elevation of the box;

Figure 3 is an enlarged view partly in section and partly in elevation illustrating in detail my improved box as herein embodied;

Figure 4 is a sectional view taken substantially on the line 4—4 of Figure 3.

As disclosed in the accompanying drawing, P denotes a post or other support adapted to be positioned at the roadside and bolted, as at 1, or otherwise suitably secured to the post P at the upper end portion thereof is a bracket B including a pair of vertically spaced and overlying plates 2. Rotatably disposed through these plates 2 and bridging the space therebetween is a shaft 3. This shaft 3 extends above the top plate 2 and is continued by a substantially perpendicularly related elongated arm 4 which is riveted, as at 5, or otherwise securely fastened to the bottom wall of the mail box M. This box M may be of such size or style desired provided it includes an upwardly swinging closure member or door C. The arm 4 at desired points spaced lengthwise thereof carries the depending loops 6 to provide a holding means for a depending frame F. This frame F includes a rear vertical member comprising spaced elongated arms 7 having their upper extremities connected, as at

8, said portion 8 being disposed through the rear loop 6. The lower end portion of each of these arms 7 is suitably secured to one of the side arms 9 comprised in an upwardly and outwardly inclined bottom member of the frame F. The forward end portion of each of these arms 9 is continued by an upwardly disposed arm 10 having its upper portion connected with the corresponding end of the second arm 10 by the intermediate member 11. This member 11 is engaged through the forward loop 6. The lower end portions of the arms 7 also have suitably secured thereto the rearwardly directed parallel arms 12, the outer ends of which are connected and formed, as at 14, to provide a bearing through which the lower portion of the shaft 3 is directed.

Held to the shaft 3 by a set screw 15 or the like is a collar 16 and interposed between the collar 16 and the top plate 2 of the bracket B is a coil spring 17 surrounding the shaft 3. One end portion of this spring 17 has an extending arm 18 which engages the set screw 15 while the opposite end portion of the spring 17 has an extending arm 19 which is connected to the top plate 2. This spring 17 provides means whereby the shaft 3 may be caused to rotate in a direction to swing the mail box M from one position to another.

The upper portions of the arms 7 carry a bolt 20 or the like bridging the space therebetween and, as herein disclosed, said bolt 20 between the arms 7 has freely mounted thereon an anti-friction sleeve 21. Extending between the arms 7 above the bolt 20 and contacting from above with the sleeve 21 is an elongated latch bar or plunger 22. This bar or plunger 22 is of a length to extend through the arms 10 to a desired distance forwardly of the frame F and the under portion of the bar or plunger 22 at the forward portion thereof is provided with a notch or recess 23 in which engages an upstanding tail piece 24 carried by the pivoted end portion of the upwardly facing hook member 25. This hook member 25 extends between the arms 10 and is pivotally held thereto by the pivot bolt 26 or the like.

The bar or plunger 22 is constantly urged rearwardly by the spring member 27, one end portion of which is anchored, as at 28, between the arms 9 while the opposite or upper end portion is suitably connected, as at 29, to the bar or plunger 22. This spring 27 serves to maintain the inner or free end of the bar or plunger 22 within the holding notch 30 provided at the transverse center of the outer marginal portion of the upper

plate 2 and which margin *a* is disposed on a curvature substantially concentric to the shaft 3.

The bar or plunger 22 is of such length that when the rear or inner end portion thereof is seated within the notch 30 the forward or outer end portion thereof will be slightly in advance of the box M. This outer end portion of the bar or plunger 22 at a desired distance inwardly thereof is formed to provide an inwardly facing shoulder 31.

As herein disclosed, the closure member or door C has its lower end portion pivotally mounted, as at 32, on the mail box M at a point below the bottom thereof whereby the closure member or door C in its opening movement swings downwardly. The lower or pivoted end portion of this closure member or door C directly above the bar or plunger 22 carries a downwardly and forwardly inclined lug 33 which, when the closure member or door C is closed and the bar or plunger 22 engaged within the notch 30, contacts from above with the bar or plunger 22 in advance of the shoulder 31. Under these conditions the mail box M preferably has its longitudinal axis disposed toward the roadway although I do not wish to be understood as limiting myself in this particular respect. The spring 27 also constantly urges the outer end of the bar or plunger 22 upwardly thus assuring proper effective coaction between the lug 33 and the shoulder 31.

When mail is to be placed into the box M by the postman he swings the closure member or door C downwardly as indicated by broken lines in Figure 3 whereupon the lug 33 will swing into a position inwardly of the shoulder 31. After the mail has been placed within the box M the postman swings the closure member or door C upwardly into closed position and during this movement the lug 33 will contact with the shoulder 31 and move the plunger or bar 22 forwardly a distance sufficiently to release the inner end portion of the bar or plunger 22 from the notch 30 whereupon the box M under the action of the spring 17 will be automatically moved or turned to a position substantially at right angles to its first or locked position. When in this second position suitable notice is given and particularly to a person at a distance that mail has been delivered.

In the event a package or other article is to be delivered and cannot be placed within the box M, such package is suspended upon the hook member 25. This will also result in a forward movement of the bar or plunger 22 sufficient to release the same from the top plate 2 so that the box M may have the desired swinging movement to its second position.

It is to be noted that the bar or plunger 22 is so mounted as to have its outer end portion readily depressed when desired. This is of advantage as it allows the householder to readily reset the mail box M in its locked position after collecting the mail or after placing mail within the box for collection by the postman.

In order that a child may readily place mail within the box M or remove the same therefrom, I find it of advantage to provide the post P with a suitably positioned platform 34. I find it of advantage to apply to the opposite sides of the frame F the closing walls 35, preferably of sheet metal, and which are connected at their inner ends by the intermediate plate 36 whereby the shaft 3 and the spring 17 thereon are effectively housed.

From the foregoing description it is thought

to be obvious that a mail box constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

1. In combination with a support, a receptacle having a movable door, means for mounting the receptacle upon the support for swinging movement, a bar operatively carried by the receptacle for endwise movement toward or from the support, means for constantly urging the bar toward the support and also to urge the outer end portion of the bar toward the receptacle, a holding member on the support engaged by the inner end portion of the bar when the receptacle is in one position, the outer end portion of the bar having an inwardly facing shoulder, and a lug carried by the door, said lug when the door is open extending rearwardly of the shoulder, said lug during the closing movement of the door contacting with the shoulder to move the bar free of the holding member to allow the receptacle to swing to a second position.

2. In combination with a support, a receptacle having a movable door, means for mounting the receptacle upon the support for swinging movement, a frame carried by and movable with the receptacle, an endwise movable bar having one end portion supported by the frame, a spring coacting with the opposite end portion of the bar to provide further support therefor and to constantly urge the bar toward the support, a holding member carried by the support with which the bar engages when the receptacle is in one position, and coacting means carried by the door of the receptacle and the bar to release the bar from the holding member when the door is moved into closed position to allow the receptacle to swing to a second position.

3. In combination with a support, a receptacle having a movable door, means for mounting the receptacle upon the support for swinging movement, a frame carried by and movable with the receptacle, an endwise movable bar having one end portion supported by the frame, a spring coacting with the opposite end portion of the bar to provide further support therefor and to constantly urge the bar toward the support, a holding member carried by the support with which the bar engages when the receptacle is in one position, yieldable means for maintaining the bar in such position, and a hook member pivotally engaged with the frame and having a tail piece engaging the bar to move the bar into released position upon movement of the hook member under the influence of a load imposed thereon.

4. In combination with a support, a receptacle having a movable door, means for mounting the receptacle upon the support for swinging movement, a frame carried by and movable with the receptacle, an endwise movable bar having one end portion supported by the frame, a spring coacting with the opposite end portion of the bar to provide further support therefor and to constantly urge the bar toward the support, a holding member carried by the support with which the bar engages when the receptacle is in one position.

tion, and means to release the bar from the holding member when the door is moved into closed position to allow the receptacle to swing to its second position.

5. In combination with a support, a receptacle having a movable door, means for mounting the receptacle upon the support for swinging movement, a frame carried by and movable with the receptacle, an endwise movable bar having one end portion supported by the frame, a spring co-acting with the opposite end portion of the bar to provide further support therefor and to constantly urge the bar toward the support, a holding member carried by the support with which the bar engages when the receptacle is in one position, means to release the bar from the holding member when the door is moved into closed position to allow the receptacle to swing to its second position, and means for swinging the receptacle to said second position.
6. In combination, a receptacle having a movable door, means carried by the receptacle for mounting the same for swinging movement, a bar operatively carried by the receptacle for endwise movement and for swinging movement toward or from the receptacle, a holding member for positioning adjacent to the receptacle for engagement by an end portion of the bar when the re-
- ceptacle is in one position, means for yieldingly supporting the opposite end portion of the bar and for urging said bar in a direction toward the holding member and also in a direction toward the receptacle, the second end portion of the bar having an inwardly facing shoulder, and a lug carried by the door, said lug when the door is opened extending rearwardly of the shoulder, said lug during the closing movement of the door contacting with the shoulder to move the bar 10 free of the holding member to allow the receptacle to swing.
7. In combination, a receptacle having a movable door, means for mounting the receptacle for swinging movement, a frame carried by and movable with the receptacle, an endwise movable bar operatively engaged with the frame, a spring co-acting with the bar and frame for constantly urging the bar in one direction and for urging the bar toward the receptacle, a holding member to 20 be engaged by the bar when the receptacle is in one position, and means carried by the door effective after the door has been opened and during the closing movement of the door to release the bar from the holding member to allow the 25 receptacle to swing to a second position.

EDWARD POPP.
